UNITED STATES PATENT OFFICE.

CHARLES WILLIAM PRICE, OF SHORNCLIFFE, ENGLAND.

WORD-COUNTER.

SPECIFICATION forming part of Letters Patent No. 710,890, dated October 7, 1902.

Application filed August 2, 1901. Serial No. 70,655. (No model.)

To all whom it may concern:

Be it known that I, CHARLES WILLIAM PRICE, armorer-sergeant, a subject of the King of Great Britain and Ireland, residing at 5 Shorncliffe Camp, Shorncliffe, in the county of Kent, England, have invented certain new and useful Improvements in Word-Counting Mechanism for Type-Writers, of which the following is a specification.

10 This invention relates to mechanism for automatically counting or recording the number of words printed by type-writing machines during the operation of the same, and also includes means for putting the said mechanism out of action when the spacing between any two words is more than the ordinary length, so as to operate only after the printing of each word. The mechanism is operated by the pressure upon or movement of 15 the word-spacing key and the number of words are recorded upon a dial or dials by means of pointers operated by gear-wheels to indicate units, hundreds, and thousands.

In order to clearly understand my invention, reference is had to the accompanying drawings, representing the said mechanism.

Figure 1 is a front view of the space-key with a portion of the base of a type-writing machine and the indicating-dial, which may 20 be clamped to a back part of the machine in full view of the operator; and Fig. 2 is a view at right angles to the same. Fig. 3 is a plan of the rocking bar cut short in parts for operating the pointers. Fig. 4 is an inside view 25 of end of front arm or crank of rocking bar, and Fig. 5 is an end view of one of the bearings of said bar. Fig. 6 is a back view of the dial, showing the operating mechanism. Fig. 7 shows the mechanism for returning the 30 pointers to their initial or zero portion, and Fig. 8 is a view showing the gear-wheel mechanism for actuating the counters.

Similar letters of reference indicate corresponding parts in all the views.

45 *a* is the space-key of any ordinary type-writer, and *b* a portion of the base of the machine. The vertical arm *a'* of the space-key bears upon and actuates the end of an arm or crank *c*, formed on or fixed to a rocking 50 bar *d*, pivoted at each end in the bearings *e*, fixed to the base of the machine, the said bar extending from front to back of the latter

underneath the base-plate. The end of the arm *c* is provided with a shifting piece *f*, formed with a flange *f'*, upon which the arm 55 *a'* of the space-key presses when the latter is forced down. The piece *f* is formed with slots with which the studs *f*² engage and is kept from shifting by means of a spring *f*³ bearing thereon. When it is desired to operate the space-key with several consecutive strokes, as in forming long spaces between any two words, the piece *f* is shifted back a short distance by means of the knob or handle *g*, so as to be clear of the arm *a'*, thus enabling the latter to descend without actuating the said arm. The rear end of the bar *d* is formed or provided with an arm or crank *h*, which is curved outwardly at its end and provided with a pin or stud *h'*.

i is the indicating-dial, carried by the support *j*, fixed to a rear portion of the machine by the clamp *j'*. The pointers *i'*, *i*², and *i*³ are operated by the gear-wheel mechanism, (shown in Fig. 8,) which is so arranged as to 75 cause the pointer *i'* to indicate units, while the pointer *i*² indicates hundreds and the pointer *i*³ indicates thousands, the dials being marked so as to indicate from one word up to one hundred thousand words. The 80 mechanism for operating the gear-wheels is shown in Fig. 6 and consists of a lever *k*, pivoted at *k'* and carrying the spring-pawl *k*², which gears with the teeth of the ratchet-wheel *k*³, mounted on the axis *k'* of the lever. 85 *k*⁴ is a retaining-spring for preventing backward movement of the ratchet-wheel.

*k*⁵ is a spring bearing upon the lever *k* to force the same downward against the fixed stop *k*⁶. The lever *k* is provided with a pivoted link *l*, which is likewise pivoted to the top of a sliding pin or pusher *l'*.

m is a rod or wire passing through the guides *m'*, fixed to the support *j* and bent over at its upper end to form a short arm *m*², 95 which passes through a slot *j*² in the support directly underneath the pin or pusher *l'*. The lower end of the rod *m* is fitted with a cap or socket *m*³, which rests upon or engages with the pin or stud *h'* on the end of the 100 arm *h*.

The operation of the mechanism is as follows: Upon pressing down the space-key *a* the arm *a'*, bearing upon the flange *f'*, turns

the arm c downward, and upon releasing the key the said arm is raised by the action of the coiled spring d' upon the rocking bar d . The arm h at the other end of the bar is likewise raised and with it the rod m , resting on its end. This action brings the arm m^2 up against the pusher l' , thus also raising the lever k , so as to cause the pawl k^2 to turn the ratchet-wheel k^3 the distance of one tooth, 10 which also operates the gear-wheels so as to move the pointer i' to indicate one unit of space, equivalent to a single word, on the face of the large dial i . Upon again pressing down the key a the rod m falls into the position 15 shown in Fig. 6, thus leaving the spring k^5 free to force the lever k down against the stop k^6 and drawing back the pawl k^2 to engage with another tooth of the ratchet-wheel. The downward motion of the rod m permits the 20 pusher l' always falling a certain distance as the space-key is pressed down, and consequently causes the pointer i' to return to its correct position on the dial for indicating each unit or word, however much it may have been 25 turned beyond the division corresponding to such position, thus making up for extra or sudden pressure on the space-key. The pointers are returned to their zero position for commencing a fresh counting of words by 30 pressing down the pusher n , Fig. 7, thus bringing the pivoted plate o in contact with the cams p to turn the same into the required position.

Having now fully described the nature of 35 my said invention, what I claim, and desire to secure by Letters Patent, is—

1. In word-counting mechanism for typewriters the combination of the space-key a, a' , the rocking bar d supported in bearings e , the arm c carried by the bar d , the spring d' 40 acting upon the said bar and arm, the shifting piece f carried at the end of the arm c and provided with the knob or handle g , the arm h also carried by the bar d , the dial i carried by the support j formed with a clamp j' , 45 the lever k carrying a spring-pawl k^2 engaging with a ratchet-wheel k^3 for actuating the dial-pointers, springs k^4 and k^5 acting upon the said wheel and lever, and stop k^6 , the link l and pusher l' connected to the lever, 50 the rod m formed with arm m^2 acting upon the pusher l' and pusher n , pivoted plate o and cams p acting upon the pointers, substantially as described.

2. In a word-counting mechanism for typewriters the combination of a rocking bar d fitted with a spring d' , an arm c fixed to one end of said bar and provided with a shifting piece f formed with a flange f' upon which the space-key acts, a spring f^3 bearing upon 60 the piece f , a handle g fixed to the latter for shifting in or out of action, an arm h fixed to the other end of the bar d and provided with a pin h' engaging with a cap or socket m^3 on the end of the rod m for actuating the pointers i', i^2 , and i^3 of the dial i , substantially as 65 described.

CHARLES WILLIAM PRICE.
